UNITED STATES PATENT OFFICE.

BURT D. STEVENS, OF EVANSTON, ILLINOIS, ASSIGNOR TO MIEHLE PRINTING PRESS & MANUFACTURING COMPANY, OF CHICAGO, ILLINOIS, A CORPORATION OF ILLINOIS.

PRINTING-PRESS DELIVERY MECHANISM.

1,365,742.

Specification of Letters Patent. Patented Jan. 18, 1921.

Application filed June 3, 1916. Serial No. 101,458.

To all whom it may concern:

Be it known that I, BURT D. STEVENS, a citizen of the United States, residing at Evanston, in the county of Cook and State 5 of Illinois, have invented certain new and useful Improvements in Printing-Press Delivery Mechanism, of which the following is a specification.

The primary objects of the invention are 10 the provision in a printing press of constructional features by means of which the printed sheet may be delivered printed side up on a vertically adjusted piling table, which latter is movable into and out of operative 15 position to receive the sheet from the impression cylinder and to afford access to working parts of the mechanism at the delivery side of the press; also the provision of an auxiliary delivery whereby, at will and 20 as occasion may arise, the pressman is enabled to divert one or more sheets and effect delivery of the same to a convenient point for inspection to determine proper registry, uniformity of inking, and other facts necessary 25 to the production of a perfect printed product.

In order that the invention may be readily understood a preferred embodiment of the same in one form of offset press is set 30 forth in the accompanying drawings and in the following detailed description based thereon. Obviously the invention is susceptible of embodiment in other and varied constructional forms to adapt the same to the 35 circumstances of use, wherefore it will be understood that the description and drawings are to be taken in an illustrative rather than in an unnecessarily limiting sense. In the drawings;—

40 Figure 1 is a general side elevational view of a press embodying the features of the invention;

Fig. 2 is a fragmentary view of the press with the side frame removed to show the 45 operating mechanism for the auxiliary delivery; and

Fig. 3 is an end view of the press broken away in a central portion.

Herein the press proper is indicated generally at 11, equipped with the ink fountain at 12, the ink distributing rolls 13, the water fountain 14, the plate cylinder 15, blanket cylinder 16, the impression cylinder 17, the feed board 18, delivery mechanism 19, the

piling table 20 and its carriage 21. The 55 parts thus far referred to form no part of the present invention and need not be described in more detail.

Normal sheet delivery.

The sheet fed to the press at 18 is taken by the grippers 22 on the impression cylinder and carried thereby in contact with and receiving its impression from the blanket cylinder 16. It is delivered by the grippers 22 to one of the grippers 23 carried by the delivery chains 19 around the sprockets 24, 24^a. By the grippers 23 the sheet is carried face down along the upper reach of said chain 19 beneath the suction hood 25 and 70 in the old and well known manner is held thereby with its printed face out of contact with the chains 19 in order to prevent smutting. It is carried by the grippers 23 around the sprocket 24^a beneath the hood 75 26 and over the suction device 27, which latter exercises a restraining action upon the trailing portion of the sheet until it is released by the grippers 23 immediately over the piling table 20, upon which table the 80 sheets build up a pile the top sheet of which is maintained in substantially constant relation to the delivery chain by the gradual lowering of the table until full. The construction and operation of the suction restraining 85 mechanism is that disclosed in patents to Henderson No. 1,156,903, and Stevens No. 1,156,940, dated October 19, 1915, and the construction and operation of the piling table is that disclosed in the patent to Rich, 90 No. 1,145,921, dated July 13, 1915.

The characteristic feature of the present invention is the manner of mounting the piling table and delivery mechanism, above described, in such manner as to arrange for 95 the moving of the same away from the press proper in order to give access to the working parts of the press at the delivery side thereof. To this end the piling table 20 is suspended from a carriage 21 which also 100 serves as a mounting for the sprockets 24, 24^a of the delivery mechanism. The carriage 21 travels by means of rollers indicated at 28 upon suitable tracks on a horizontal frame 31, supported at one end upon the 105 frame of the printing press and at the other end upon standards 32. The standards and frame carry pillow blocks 31 within which

is journaled a shaft 32, provided with a hand wheel 33, and having fixed thereon a pinion 34 in mesh with a rack 35 on the carriage.

- 5 It will be obvious that by the rotation of the hand wheel 33 the carriage with its burden of delivery mechanism and piling table may be moved from the position shown in full lines in Fig. 1 to that indicated in
 10 dotted lines in said figure, the full line position being the normal operative position and the dotted line position being that with the delivery mechanism and table removed from the press in order to give access thereto. The
 15 removal of the piling table and delivery mechanism in this manner provides a passageway and space for a workman between the press and the said delivery mechanism and piling table without the necessity of
 20 having an extension delivery at a considerable elevation in order to provide this accessibility.

Auxiliary sheet delivery.

- 25 In printing presses of this general type it has been proposed to take the sheet from the impression cylinder and deliver the same at that side of the press opposite the feed board in which delivered position the top
 30 sheet would be exposed to view by the pressman and the quality of the work could be inspected from time to time. An objection to this mode of delivery is that the sheets are delivered in a position near the floor
 35 and where they would be in the way of the pressman, involving the carrying away of the printed sheets at frequent intervals. In order to provide for a piling table with a wide range of vertical movement adapted
 40 to accommodate a large number of sheets and to permit the same to be carried away by a truck in large quantities, it has been found desirable to deliver the sheets as previously described on the same side of the
 45 press as the feed board, but this has necessitated frequent trips by the pressman to the delivery table in order to inspect the work. In order to combine the advantages of a piling table placed beneath the feed
 50 board and at the same time to facilitate inspection of the sheets when desired, the present arrangement is designed.

In addition to the normal delivery at the feed side of the press, by means of the grippers traveling around the cylinder or sprocket 24 an auxiliary delivery cylinder 36 is provided for delivering sheets for inspection upon the table 37. To control this auxiliary delivery, the following mechanism is provided: On the end of the blanket cylinder 16 is formed a cam groove 38 for traverse by a roller 39 carried by one arm 40 of an angle lever fulcrumed at 41 and having another arm 42. This arm 42
 65 has fixed thereon a stud 43 which plays

within a slot 44 of a link bar 45. Upon this link bar 45 is pivoted at 46 a latch 47 adapted to hook over the stud 43 and lock the lever arm 42 and the link bar 45 together. The opposite end of the link bar 45 is pivoted at 48 to an arm 49 connected to the eccentric shaft 50 which acts upon the bearings of the auxiliary cylinder 36 to move the same bodily toward and from the impression cylinder 17. An arm 51 extending beyond the eccentric 50 has a lateral cam face adapted to bear against the stud pin 52 and project the same into the path of the grippers 22 carried by the impression cylinder.

A lever 53 fastened to eccentric shaft 50 has a slide link 54 pivoted at 55 and sliding in 56. Link 57 is connected at 58 to 54 at one end and to 59 on the cam 60 at the other end, which cam is in the path of the gripper operating lever 61.

The operation is as follows: If the pressman desires to inspect a sheet upon the table 37 he pulls the hand lever 62 and thereby drops the latch 47 into engagement with the stud 43 causing the link bar 45 to partake of the motion of the lever arm 42 shifting the eccentric shaft 50 to bring the auxiliary cylinder 36 into operative engagement with the impression cylinder 17 and permit its grippers 63 to take the sheet therefrom, the stud pin 52 having been projected into the path of the grippers 22 to actuate the latter to release the sheet as it is taken by the grippers 63.

The lever 53 which is fastened to eccentric shaft 50 moves the slide link 54 to the left causing the cam 60 through the link 57 to advance to a position to close the grippers 63 on the sheet the instant the grippers 22 release it from the impression cylinder. The reverse movement of the lever 62 restores the auxiliary cylinder 36 to a position where it will not take the sheet from the impression cylinder 17 but permit the same to be carried to its position of normal delivery to the grippers 23, as previously described.

I claim:

1. The combination with a printing press, of a pile delivery including a vertically movable pile table and a sheet conveying mechanism to transfer the sheets from the press to the table, and mechanism for moving said pile delivery bodily from a normal operative position closely adjacent the press to an inoperative position spaced from the press to provide access to that end of the press.

2. The combination with a printing press, of a pile delivery at the feeder end of the press and including a vertically movable pile table and sheet conveying mechanism to transfer the sheets from the press to the table, and mechanism for moving said pile delivery bodily from a normal operative position closely adjacent the press to an in-

operative position spaced from the press to provide access to that end of the press.

3. The combination with a printing press, of a pile delivery beneath the feed board 5 and including a vertically movable pile table and a sheet conveying mechanism to transfer the sheets from the press to the table, and mechanism for moving said pile table bodily from a normal operative position 10 closely adjacent the press to an inoperative position spaced from the press to provide access to that end of the press.

4. In a printing press, the combination with the printing members, and a sheet pile 15 delivery at the feeder end of the press, of an auxiliary sheet delivery at the opposite end of the press, and means to bring either of the deliveries alternatively into operation at will, whereby to take the sheets from the 20 impression member and deliver them onto the pile or into position for inspection by the pressman.

5. In a printing press, the combination with the printing members, and a sheet pile 25 delivery at the feeder end of the press movable bodily from a normal operative position closely adjacent the press to an inoperative position spaced from the press to afford access to that end of the press, of an auxiliary 30 sheet delivery at the opposite end of the press, and means to bring the auxiliary delivery into operation at will whereby to deliver a sheet into position for inspection by the pressman.

35 6. In an offset printing press, delivery mechanism adapted for use in combination with the plate, blanket and impression cylinders and comprising a sheet piling table, and sheet conveying mechanism arranged 40 to take the printed sheet from the impression cylinder and convey the same to the pile, of an auxiliary sheet delivery including a cylinder provided with means to take the sheet from the impression cylinder and 45 convey the same to a point of easy inspection by the pressman, and means within the control of the pressman to bring either set of sheet-taking devices alternatively into operation at will.

50 7. In an offset printing press, delivery mechanism adapted for use in combination with the plate, blanket and impression cylinders and comprising a sheet piling table at the feeder end of the press, and sheet conveying mechanism including grippers arranged to take the printed sheet from the impression cylinder and convey the same to the pile, of an auxiliary sheet delivery at the opposite end of the press for conveying the 55 sheet to a point of easy inspection by the pressman and including grippers to take the sheet from the impression cylinder, and means within the control of the pressman to bring either set of sheet-taking grippers 60 alternatively into operation at will.

8. In an offset printing press, delivery mechanism adapted for use in combination with the plate, blanket and impression cylinders, and comprising a sheet piling table, and sheet conveying mechanism arranged to 70 take the printed sheet from the impression cylinder and convey the same to the pile, of an auxiliary sheet delivery including a cylinder provided with grippers to take the sheet from the impression cylinder and convey the same to a point of easy inspection by the pressman, the sheet-taking devices of the auxiliary cylinder disposed in advance of the sheet taking devices of the pile delivery but inactive, and means within the 75 control of the pressman to shift the sheet-taking devices of the auxiliary delivery into action to take the sheet from the impression cylinder before reaching the sheet-taking devices of the pile delivery. 85

9. In an offset printing press, delivery mechanism adapted for use in combination with the plate, blanket and impression cylinders and comprising a sheet piling table at the feeder end of the press, and sheet 90 conveying mechanism including grippers arranged to take the printed sheet from the impression cylinder and convey the same to the pile, of an auxiliary sheet delivery for conveying the sheet to a point of easy inspection by the pressman and including grippers to take the sheet from the impression cylinder, the sheet-taking devices of the auxiliary delivery disposed in advance of the sheet-taking devices of the pile delivery but 95 spaced from the impression cylinder to render them inactive, and means within the control of the pressman to shift the auxiliary cylinder into position to bring its sheet-taking devices into action to take the sheet 100 from the impression cylinder before reaching the sheet-taking devices of the pile delivery. 105

10. In an offset printing press, delivery mechanism adapted for use in combination with the plate, blanket and impression cylinders and comprising a sheet piling table at the feeder end of the press, and sheet conveying mechanism including grippers arranged to take the printed sheet from the impression cylinder and convey the same to the pile, of an auxiliary sheet delivery for conveying the sheet to a point of easy inspection by the pressman and including grippers to take the sheet from the impression cylinder, the sheet-taking devices of the auxiliary delivery disposed in advance of the sheet-taking devices of the pile delivery but spaced from the impression cylinder to render them inactive, and means within the 115 control of the pressman to shift the auxiliary cylinder into position to bring its sheet-taking devices into action to take the sheet from the impression cylinder before reaching the sheet-taking devices of the pile delivery. 120

11. In an offset printing press, delivery mechanism adapted for use in combination with the plate, blanket and impression cylinders and comprising a sheet piling table at the feeder end of the press, and sheet conveying mechanism including grippers arranged to take the printed sheet from the impression cylinder and convey the same to the pile, of an auxiliary sheet delivery for conveying the sheet to a point of easy inspection by the pressman and including grippers to take the sheet from the impression cylinder, the sheet-taking devices of the auxiliary delivery disposed in advance of the sheet-taking devices of the pile delivery but spaced from the impression cylinder to render them inactive, and means within the 125 control of the pressman to shift the auxiliary cylinder into position to bring its sheet-taking devices into action to take the sheet from the impression cylinder before reaching the sheet-taking devices of the pile delivery. 130

livery, said means comprising mechanism for tripping the auxiliary cylinder with its sheet-taking grippers into operative relation to the impression cylinder and for 5 simultaneously releasing the sheet from the grippers of the impression cylinder to the grippers of the auxiliary cylinder.

In witness whereof I have hereunto signed my name in the presence of two subscribing witnesses.
